UNITED STATES PATENT OFFICE

BEN J. CRIST, OF ELLSWORTH, MINNESOTA

PUMP JACK

Application filed January 16, 1928. Serial No. 247,169.

This invention relates to the class of pumps and pertains particularly to a pump jack.

The primary object of this invention is to provide, in a manner as hereinafter set forth, an improved means for mechanically operating the piston and piston rod of a pump of the character normally operated by a pivoted handle or lever.

Another object of the invention is to provide, in a manner as hereinafter set forth, an improved mechanical structure for the operation of a pump of the character above described, which can be mounted directly upon the pump casing without taking an unneeded amount of space and thereby permitting the structure to be used upon pumps which are located in positions having small amount of surrounding room.

A further object of the invention is to provide, in a manner as hereinafter set forth, an improved pump jack which is of simple but strong and durable construction, easily installed and comparatively inexpensive to manufacture and set up.

Numerous other objects and advantages of this invention will become apparent as the description of the same proceeds and the invention will be best understood from a consideration of the following detailed description taken in connection with the accompanying drawings forming a part of this specification, with the understanding, however, that the invention is not confined to any strict conformity with the showing of the drawings but may be changed or modified so long as such changes or modifications mark no material departure from the salient features of the invention as expressed in the appended claim.

In the drawings:

Figure 1 shows a pump in side elevation showing the jack embodying the present invention applied thereto.

Figure 2 is a front elevational view of the pump structure shown in Figure 1.

Figure 3 is a plan view of the pump jack structure embodying this invention.

Figure 4 is a sectional view taken upon the line 4—4 of Figure 3.

Figure 5 is a sectional view taken substantially upon the line 5—5 of Figure 1.

Figure 6 is a sectional view taken substantially upon the line 6—6 of Figure 2.

Figure 7 is a sectional view showing the 55 method of connecting the cross beam to an adjustable side bar.

Referring now to the drawings in detail wherein like numerals of reference indicate corresponding parts throughout the several 60 views, the numeral 1 indicates the body of a hand operated pump of usual construction, including the handle 2, pump rod 3, and nozzle 4.

The jack structure embodying the present 65 invention comprises a cast base or bed plate 5, a portion of one side of the plate adjacent the front edge, extending laterally as at 6, a depression being formed in the plate adjacent the lateral extension 6, to provide an oil pan 7. At the front and rear of the oil pan 7 the plate is formed to provide half bearings 8 and 9 respectively, in which bearings a stub shaft 10 is mounted and held in place by the cap bearings 11 and 12, as more clearly 70 shown in Figure 3. Carried upon the shaft 10 between the bearings 8 and 9 is a pinion drive gear 13, the periphery of which projects a sufficient distance beyond the adjacent side edge of the bed plate pan 7 to 75 engage a gear hereinafter described. The outer end of this shaft carries the belt pulley 14 over which a suitable drive belt (not shown) may be engaged.

Cast integral with and across the rear edge 80 of the bed plate 5 is a bearing sleeve 15 in which is mounted a shaft 16 which carries upon that end adjacent the edge of the bed plate beyond which the pinion gear 13 projects, a relatively large beveled gear 17 the 85 teeth of which mesh with the teeth of the pinion drive gear 13. The other end of the shaft 16 carries the crank arm 18 which is provided adjacent the free end thereof with a series of apertures 19 in which a pin 20 90 may be secured. The gear 17 has cast integral therewith the counter balance weight 21 which is provided with a radially extending series of apertures 22 which are aligned 95 with the apertures in the crank arm 18. 100

Cast with or otherwise secured to the bearing sleeve 15 is one half of a clamp collar which half is indicated by the numeral 23 with which is associated a complementary half 24, the ears 25 of the two halves being drawn together by appropriate securing elements such as the bolt members 26. This clamp collar is engaged about the lower portion of the pump body 1 as shown in Figure 1 at the proper point thereon to correspond with the height of the supporting legs 27 formed adjacent the forward edge of the bed plate 5, to maintain the plate in substantially horizontal position.

15 A suitable cover or hood 28 is provided to overlie the pinion gear 13, which hood is secured to the bed plate 5 in the manner shown. Associated with this hood is an upwardly extending curved shield 29 which overlies a portion of the face of the gear 17 to prevent the entanglement of any article in this gear.

16 A pair of longitudinally adjustable bars, each indicated by the numeral 30, is provided, each of which comprises a lower portion 31 and an upper portion 32, these portions being preferably of channel construction so that each of the upper portions 32 is of smaller cross sectional area than the lower portion and slidably engages in a lower portion in the manner shown, each of the portions being provided with longitudinally extending series of apertures 33 which receive the bolts 34 to maintain the bars at the desired adjusted length.

17 Each of the bar sections 31 has secured in the lower end thereof a clamp member 35, one of which engages the pin 20 carried by the arm 18 while the other engages a similar pin 26 fitted into one of the apertures 22 in the gear counter balance body 21.

18 Each of the upper sections 32 has secured thereto a bearing 37 each of which receives a trunnion pin 38 carried by and projecting from the end of a cross head 39, the bars 30 being thus connected by this cross head. A suitable retaining element such as a cotter key may be passed through the pins 38 as shown. The central portion of the cross head 39 is formed to provide a seat 40 for the reception of the upper end of a pump rod 41. A cap 42 is secured over the seat 40 by the screws 43, which holds the rod in position, an additional securing element being carried by the cap in the form of a binding screw 45 which bears against the rod as shown in Fig. 6.

19 From the foregoing description it will be readily seen that in a pump jack of this character a small electric or gasoline motor can be employed to operate a pump of the character described or any other type wherein an exposed reciprocating pump rod is employed.

Having thus described my invention what I claim is:

20 A pump jack stand comprising a horizontally disposed base plate, a bearing cast

integral with and extending across one end of said plate, a pump clamp section formed on the bearing, depending legs formed on the opposite end of the base plate from said bearing and clamp section, an oil pan cast in said plate between the bearing and legs, and bearing sections formed on opposite sides of the plate and communicating with said pan.

In testimony whereof I affix my signature.

BEN J. CRIST.
